UNITED STATES PATENT OFFICE.

JAMES DANIEL JOYCE, OF PHILADELPHIA, PENNSYLVANIA.

WINDING MACHINE.

Application filed February 6, 1925. Serial No. 7,280.

This invention relates to winding machines and more especially to improvements in the general type of machine disclosed in my copending application, Serial No. 668592 filed January 25, 1924 on winding machines.

It is an object of my invention to provide a machine adapted to operate simultaneously a plurality of spindles from a common drive mechanism, each spindle forming a portion of a separately mountable spindle unit which includes all of the elements essential to a separate winding machine, the spindle itself, operative connecting means between the spindle and the common drive mechanism, a traversible thread guide and traversing means therefor and suitable stop devices.

It is a further object of my invention to provide an improved type of traverse mechanism which is driven directly from the spindle shaft. This insures a proper ratio of spindle rotation speed to guide traverse speed. Additionally it does away with the necessity of the rock shafts, rock shaft operating mechanisms, the traverse arm clutches and clutch throw-out mechanism.

Other objects of my invention will appear in the following specification and claims and will be disclosed in the accompanying drawings in which—

Figure 1 is a side elevation of one of my winding heads;

Figure 2 is a top plan view of the structure shown in Figure 1;

Figure 3 is a detail perspective of my stop mechanism;

Figure 4 is a detail cross-section of my progressive thread guide carrier;

Figure 5 is a detail of my spindle shaft;

Figure 6 is a detail perspective of my traverse and stop mechanism;

Figure 7 is a detail in end elevation of my cam drive;

Figure 8 is a side elevation of my cam drive casing with side plates removed;

Figure 9 is a detail partly in cross section, of my progression wheel.

Figure 10 is a plan view showing my driving means.

The frame 1 has mounted therein in suitable bearings 2 a shaft 3 adapted to be rotated by any suitable means. Fixedly secured to the shaft 3 are a plurality of friction drive wheels 4 each of which is adapted to engage friction disks 5 to drive a pair of oppositely mounted spindles 6.

The spindle 6 is screw-threadedly secured

in the end of a spindle shaft 7 which is rotatably mounted in suitable friction reducing bearings 8 in an auxiliary frame member or bracket 9 detachably secured by bolts 10 to the frame 1. The spindle shaft is secured against endwise movement by collars 11 and 12 fixed thereto and abutting the bearings 8.

Fixedly secured on the shaft 7 is a worm sleeve 13 having a four thread worm 14 cut in its outer surface. The forward end 15 of the worm is of a reduced diameter to provide an abutment or shoulder 16. The forward end 15 of the worm sleeve is cut away into substantially semi-cylindrical form to enable it to have driving engagement with a similarly cut portion 17 of a sleeve 18 rotatably mounted on the shaft. The friction disk 5 is fixedly secured to the sleeve 18. Loosely mounted on the sleeve 18 is a compression spring 19 having one end abutting the disk 5. This spring forces the disk 5 into driving engagement with the driving wheel 4 to rotate the spindle.

A brake lever 20 is pivotally mounted on the bracket 9 by means of a stud 21. The upper arm 22 of the lever 20 is formed to receive a brake 23 of some suitable material such as fiber or rubber. The other arm 24 of the lever 20 has a portion which extends horizontally in a direction substantially parallel to the spindle. A tension spring 25 of greater strength than the spring 19 is secured at one of its ends to the rearward end of the arm 24 and at its other end to a suitable stud 26 fixed in the bracket. A flange 27 on the arm 24 is adapted to be engaged by an arm 28 which is fixed on an operating control rod 29. The control rod 29 is rotatably mounted in the bracket 9 at 30 and 31 and is limited against endwise movement by the set collars 32 and 33.

Fixedly secured to the operating control rod 29 is a collar 34 to which is fixed an arm 35. On the rearward end of the rod 29 is a suitable handle 36. A stop control rod 37 is longitudinally slidably mounted in bearings 38 and 39 of the bracket and in a bearing 40 in an auxiliary bracket 41 secured to the bracket.

A collar 42 is fixed on the stop control rod by means of a set screw 42a. A light compression spring 43 mounted between the bearing 38 and the collar 42 tends to force the rod 37 forward. Forward movement of the rod is limited by a pin 44. When the handle 36 is turned in a counter-clockwise

direction the arm 35 is moved out of the path of the collar 42 and the rod 37 moves forward under the influence of the spring 43 until its forward motion is arrested by pin 44. Rotation of the rod 29 also raises the arm 28, lifts the arm 24 against the action of spring 25, and moves the brake 23 out of contact with the disk 5 thus permitting the spring 19 to force the disk into driving engagement with wheel 4 and putting the spindle into rotation.

When rotative pressure is now released on the handle 36 the rod 29, under the influence of the spring 25 acting through arm 24, flange 27, and arm 28, tends to rotate in a clockwise direction.

The collar 42 has now moved under the arm 35 and the arm 35 will rest on the said collar until the rod 37 is moved backward.

20 The spindle thus continues to engage operatively the wheel 4 until the rod 37 is moved backward.

Slightly ahead of the collar 42 on the rod 37 another collar 45 is fixed by set screw 46. Fixed to this collar is a forked arm 47 which straddles the traverse rod 70. The rod 70 is adapted to be reciprocated by means hereinafter to be described and slides in bearings 71 and 72 of the bracket and auxiliary bracket. The arm 47 has a flanged portion 48 which serves to limit the downward motion of an arm 49, the upward motion of said arm being limited by the traverse bar 70.

35 Fixed on the traverse bar 70 is a collar 75 which, in the backward movement of the traverse rod, does not quite reach the arm 47 and so does not move the rod 37 backward. The arm 49 has a turned over or flanged end 50 of such length that when this flange is moved into the path of the collar 73 the arm 47 and rod 37 will be moved, by the traverse rod, backward to such a degree that the arm 35, under the influence of spring 25, falls in front of the collar 42. This clockwise rotation of rod 29 permits the spring 25 to act on the brake lever 20 pushing the brake against the disk 5, forcing the same out of contact with the wheel 4 and simultaneously braking the said disk.

40 A stop rod 51 is rotatably mounted in suitable bearings 52, 53 and 54 in the bracket and is limited in endwise movement by collars 55 and 56 fixedly secured thereto. The 45 arm 49 heretofore discussed is fixed to the collar 56 and oscillates therewith. Between the collar 56 and the bearing 53 a collar 57 is rotatably mounted on rod 51. Fixed to collar 57 is a thread arm 58 having a flexible extension 59 and an eyelet 60. The 50 thread arm is additionally provided with a forked portion 61 which straddles a horizontally extending bent portion 62 of the arm 49. The forked portion loosely engages 55 the arm portion 62 so that oscillation of arm

58 results in oscillation of arm 49. The purpose of this will be understood when it is noted that the thread is fed to the spindle from above. The thread passes through the eyelet 60 on its way to the thread guide 63 and it will be seen that the draft on the thread thus tends to hold the arm extension 59 up. This results in the forked portion 61 being moved downwardly thus, through arm portion 62, rotating arm 49 and moving flange 50 out of the path of the collar 73 thus permitting the winding to proceed. If the thread being wound to this spindle breaks the extension 59 will fall and the flange 50 will be moved into the path of the collar 73 stopping the machine.

50 The thread guide 63 is mounted on a yoke 64 slidably and rotatably mounted by means of sleeves 65 on the screw-threaded portion 74 of the traverse rod 70. Between the 55 sleeves 65 a sleeve 66, to which the progression or contact wheel 67 is fixedly secured, is also mounted on the rod portion 74. This last named sleeve has a sliding fit with the thread rod and has cutaway portion 90 through which a portion of an arm 68 is adapted to extend to engage the threaded rod as a single toothed gear. The arm 68 is pivotally secured to the wheel 67 and is spring-pressed into engagement with the 95 threaded rod by bent leaf spring 69. This permits of the free movement of the guide in either direction along the threaded rod without rotation of the wheel as in setting the guide preparatory to winding. Rotation of 100 the wheel by contact with the yarn being wound causes the guide to be moved along the rod. An arm 64 is mounted on the threaded rod and has a forked portion 64^b following the rod 51 and a portion 64^c 105 adapted to act as a limit to rotation of the yoke away from the spindle.

55 The winding may be stopped manually at any time by grasping any portion of the rod 37 and moving it backward. The rod is 110 additionally provided with a stop arm 37^a adjustably mounted on the rod 37 which ends to a point in proximity to the threaded rod and is adapted to be engaged by the sleeve 65 to move the rod 37 backward when the 115 winding has progressed to the desired length.

60 The traverse rod 70 is secured by a link 75 to a traverse arm 76 pivoted at 76' to a stud 77 secured to the frame. Substantially midway of its length the arm 76 is provided with a cam follower 78 adapted to follow in cam slot 79 formed in the face of a cam block 80 rotatably mounted in a suitable bearing 81 in the frame. A portion of 125 the surface of the cam block is formed to provide a worm gear 82 adapted to mesh with and be driven by the worm 14. The ratio between the worm and the worm gear may be any that is desired but I have so de- 130

signed my four thread worm and worm gear that there will be thirteen revolutions of the spindle to each complete revolution of the cam block or six and one-half revolutions 5 to every throw of the traverse rod.

The operation of my device has been explained in detail as the disclosure progressed and, it is believed, will be clearly understood by those skilled in the art.

10 I claim—

1. In combination, in a winding machine, a constantly rotating shaft, a rotative spindle shaft, a spindle on said spindle shaft, a traverse guide reciprocating means operatively driven by said spindle shaft to traverse said guide, means operatively connecting said spindle shaft to said constantly rotating shaft, and means automatically movable into the path of said reciprocating means to disconnect said spindle shaft from said constantly rotating shaft when the thread being fed to said spindle breaks.

2. In combination, in a winding machine adapted to wind simultaneously a plurality of winding heads, a frame, a plurality of winding elements mounted in said frame, a common drive means including a constantly rotating shaft, a rotating spindle shaft, and a reciprocating traverse bar, means operatively connecting said spindle to said constantly rotating shaft to drive the former, an oscillatory arm, a link to connect said arm and said bar to reciprocate the latter, a worm on said spindle shaft, a gear driven by said worm, said gear having a cam slot in one face thereof, and a follower on said arm adapted to engage in said slot to oscillate said arm.

3. In combination, in a winding machine adapted to wind simultaneously a plurality of winding heads, a frame, a plurality of winding elements mounted in said frame, a common drive means including a constantly rotating shaft, a rotating spindle shaft, and a reciprocating traverse bar, means spring-pressed to operatively connect said spindle to said constantly rotating shaft to drive the former, an oscillatory arm, a link to connect said arm and said bar to reciprocate the latter, and means operatively connecting said spindle shaft to said arm to oscillate the latter.

4. In combination, in a winding machine adapted to wind simultaneously a plurality of winding heads, a frame, a plurality of winding elements mounted in said frame, a common drive means including a constantly rotating shaft, a rotating spindle shaft, and a reciprocating traverse bar, means spring-pressed to operatively connect said spindle to said constantly rotating shaft to drive the former, an oscillatory arm, a link to connect said arm and said bar to reciprocate the latter, a worm on said spindle shaft, a gear driven by said worm, said gear having a

cam slot in one face thereof, and a follower on said arm adapted to engage in said slot to oscillate said arm.

5. In combination, in a traverse mechanism, in a winding head, a reciprocating bar 70 and a traverse guide thereon, an oscillatory arm, a link to connect said arm and said bar to reciprocate the latter, a rotating spindle shaft, means operatively connecting said spindle shaft to said arm to oscillate the latter, drive mechanism, means on said shaft spring-pressed to engage said drive mechanism to rotate said shaft, and traverse operated stop mechanism operating to disconnect said spring-pressed means from said 80 drive mechanism.

6. In combination, in a traverse mechanism, in a winding head, reciprocating bar and a traverse guide thereon, an oscillating arm, a link to connect said arm and said bar to reciprocate the latter, a rotating spindle shaft, a worm on said shaft, a gear driven by said worm, said gear having a cam slot in one face thereof, and a follower on said arm adapted to engage in said slot to oscillate said arm, drive mechanism, means on said shaft spring-pressed to engage said drive mechanism to rotate said shaft, and traverse operated stop mechanism operating to disconnect said spring-pressed means from said 90 drive mechanism.

7. In a winding machine, in combination, a rotative winding spindle, a reciprocating guide and traverse bar operated by said spindle, means to operate said spindle, and means to reciprocate the guide, of stop devices, a rod to control said stop devices, and means to move said rod longitudinally to operate said stop devices.

8. In a winding machine, in combination, 105 a rotative winding spindle, a reciprocating guide and traverse bar operated by said spindle, means to operate said spindle, and means to reciprocate the guide, of spring operated stop devices, a rod to control said 110 stop devices, and means movable into the path of said traversing means to cause the same to move said rod longitudinally to operate said stop devices when the thread being fed to said spindle breaks.

9. In a winding machine, in combination, a rotative winding spindle, a reciprocating guide and traverse bar operated by said spindle, means to operate said spindle, and means to reciprocate the guide, of stop devices, a rod to control said stop devices, and means on said rod adapted to be engaged to move said rod longitudinally to operate said stop devices when the winding is completed.

10. In combination, in a winding machine, a frame, a rotatable spindle shaft mounted in bearings in said frame, said spindle shaft being comprised of two aligned 120 constantly engaging portions one of which is fixed against and the other capable of 130

limited longitudinal motion, a compression spring mounted concentrically of said shaft and tending to space said shaft portions longitudinally, drive mechanism, and means on said movable shaft portion pressed by said spring to operatively engage said drive mechanism to rotate said spindle shaft, and means adapted to shift said longitudinally movable spindle shaft portion to disengage said last named means from said drive mechanism, a thread guide and traverse bar therefor, means for traversing said bar, and means on said longitudinally fixed shaft portion for operating said traversing means.

11. In combination, in a winding machine, a frame, a rotatable spindle shaft mounted in bearings in said frame, said spindle shaft being comprised of two aligned constantly engaging portions one of which is fixed against and the other capable of limited longitudinal motion, of drive mechanism, a compression spring loosely mounted concentrically of said shaft and tending to space said shaft portion longitudinally, and means on said movable shaft portion to operatively engage said drive mechanism to rotate said spindle shaft.

12. In combination, in a winding machine, a frame, a rotatable spindle shaft mounted in bearings in said frame, said spindle shaft being comprised of two aligned constantly engaging portions one of which is fixed against and the other capable of limited longitudinal motion, of drive mechanism, a compression spring loosely mounted concentrically of said shaft and tending to space said shaft portions longitudinally, and means on said movable shaft portion pressed by said spring to operatively engage said drive mechanism to rotate said spindle shaft, and means to disengage said last named means from said drive mechanism.

13. In combination, in a winding machine, a frame, a rotatable spindle shaft mounted in bearings in said frame, said spindle shaft being comprised of two aligned constantly engaging portions one of which is fixed against and the other capable of limited longitudinal motion, of drive mechanism, a compression spring loosely mounted concentrically of said shaft and tending to space said shaft portions longitudinally, and means on said movable shaft portion pressed by said spring to operatively engage said drive mechanism to rotate said spindle shaft, and means to automatically disengage said last named means from said drive mechanism when the thread being wound breaks or when the winding is completed.

14. In combination, in a winding machine, a frame, a rotatable spindle shaft mounted in bearings in said frame, said spindle shaft being comprised of two aligned constantly engaging portions one of which is fixed

against and the other capable of limited longitudinal motion, of drive mechanism, a compression spring loosely mounted concentrically of said shaft and tending to space said shaft portions longitudinally, and means on said movable shaft portion pressed by said spring to operatively engage said drive mechanism to rotate said spindle shaft, and means adapted to shift said longitudinally movable spindle shaft portion to disengage said last named means from said drive mechanism.

15. In combination, in a winding machine, a frame, a rotatable spindle shaft mounted in bearings in said frame, said spindle shaft being comprised of two aligned constantly engaging portions one of which is fixed against and the other capable of limited longitudinal motion, of drive mechanism, a compression spring loosely mounted concentrically of said shaft and tending to space said shaft portions longitudinally and means on said movable shaft portion pressed by said spring to operatively engage said drive mechanism to rotate said spindle shaft, and means adapted to shift said longitudinally movable spindle shaft portion to automatically disengage said last named means from said drive mechanism when the thread being wound breaks or when the winding is completed.

16. In combination, in a winding machine, a frame, a rotatable spindle shaft mounted in bearings in said frame, said spindle shaft being comprised of two aligned constantly engaging portions one of which is fixed against and the other capable of limited longitudinal motion, a compression spring mounted concentrically of said shaft and tending to space said shaft portions longitudinally, drive mechanism, and means on said movable shaft portion pressed by said spring to operatively engage said drive mechanism to rotate said spindle shaft, means to automatically disengage said last named means from said drive mechanism when the thread being wound breaks or when the winding is completed, a thread guide and traverse bar therefor, means for traversing said bar, and means on said longitudinally fixed shaft portion for operating said traversing means.

17. In combination, in a winding machine, a frame, a rotatable spindle shaft mounted in bearings in said frame, said spindle shaft being comprised of two aligned constantly engaging portions one of which is fixed against and the other capable of limited longitudinal motion, a compression spring mounted concentrically of said shaft and tending to space said shaft portions longitudinally, drive mechanism, and means on said movable shaft portion pressed by said spring to operatively engage said drive mechanism to rotate said spindle shaft,

means to automatically disengage said last named means from said drive mechanism when the thread being wound breaks or when the winding is completed, a thread 5 guide and traverse bar therefor, an oscillating arm for traversing said bar, a cam gear adapted to oscillate said arm, and a worm on said fixed shaft portion having driving engagement with said cam gear.

10 18. In combination, in a winding machine, a frame, a rotatable spindle shaft mounted in bearings in said frame, said spindle shaft being comprised of two aligned constantly engaging portions one of which is fixed 70 against and the other capable of limited longitudinal motion, a compression spring mounted concentrically of said shaft and tending to space said shaft portions longitudinally, drive mechanism, and means on 15 said movable shaft portion pressed by said spring to operatively engage said drive mechanism to rotate said spindle shaft, means to automatically disengage said last named means from said drive mechanism 20 when the thread being wound breaks or when the winding is completed, a thread 75 guide and traverse bar therefor, an oscillating arm for traversing said bar, a cam gear adapted to oscillate said arm, and a compound worm on said fixed shaft portion having driving engagement with said cam gear.

25 19. In combination, in a winding machine, a frame, a rotatable spindle shaft mounted in bearings in said frame, said spindle shaft being comprised of two aligned constantly engaging portions one of which is fixed 80 against and the other capable of limited longitudinal motion, a compression spring mounted concentrically of said shaft and tending to space said shaft portions longitudinally, drive mechanism, and means on 85 said movable shaft portion pressed by said spring to operatively engage said drive mechanism to rotate said spindle shaft, means to automatically disengage said last named means from said drive mechanism 90 when the thread being wound breaks or when the winding is completed, a thread 95 guide and traverse bar therefor, an oscillating arm for traversing said bar, a cam gear adapted to oscillate said arm, and a compound worm on said fixed shaft portion having driving engagement with said cam gear.

40 20. In combination, in a winding machine, a frame, a spindle shaft rotatably mounted in said frame, means for rotating said spindle, a traversing thread guide for said spindle operated by a transverse mechanism driven from said spindle shaft, a stop mechanism for said spindle shaft, a collar on 45 said traverse mechanism which in the travel 100 of the traverse mechanism stops short of

the stop mechanism, and means automatically movable into the path of said collar to cause the same to operate said stop mechanism when the thread breaks or when the bobbin is fully wound. 105

21. In combination, in a winding machine, a frame, a rotatable spindle shaft mounted in bearings in said frame, said spindle shaft being comprised of two aligned constantly engaging portions one of which is fixed 75 against and the other capable of limited longitudinal motion, of drive mechanism, a compression spring loosely mounted concentrically of said shaft and tending to space 80 said shaft portions longitudinally, and means on said movable shaft portion pressed by said spring to operatively engage said drive mechanism to rotate said spindle shaft, means adapted to shift said longitudinally movable spindle shaft portion to disengage 85 said last named means from said drive mechanism, and means for braking said drive engaging means.

22. In combination, in a winding machine, a constantly rotating shaft comprising a 90 drive means common to a plurality of winding spindles, a plurality of rotative spindle shafts, a traverse guide for each spindle shaft, reciprocating means operatively driven by said spindle shafts to traverse 95 said guides, means operatively connecting said spindle shafts to said constantly rotating shaft, said common drive means including a plurality of friction drive wheels, each spindle rotating means comprising a friction disk mounted on the shaft of its spindle and adapted to be engaged with and disengaged from its respective driving wheel without interruption to the 100 operation of the remaining winding elements.

23. In combination, in a winding machine adapted to operate simultaneously a plurality of winding heads, a frame, a plurality of winding elements mounted in said frame, a drive means common to all of said winding heads comprising a constantly rotating shaft having mounted thereon a plurality of drive wheels, a rotatable spindle-bearing shaft for each of said winding heads having mounted thereon a friction disk adapted to engage with and to be disengaged from its respective drive wheel, a reciprocating traverse bar for each spindle, means operatively connecting said spindle shaft to said reciprocating bar to drive said bar comprising an oscillatory arm, a link to connect said arm and said bar to reciprocate the latter, a worm on said spindle shaft, a gear driven by said worm, said gear having a cam slot in one face thereof, a follower on said arm adapted to engage said slot to operate said arm, and means operated by the traverse mechanism for automatically disengaging the friction disk from its drive wheel. 110 115 120 125 130

24. In a winding machine, the combination of a winding-spindle, a thread-guide, traverse means including an oscillating traverse arm for reciprocating the thread guide, driving means for rotating the winding spindle and oscillating the traverse arm, stopping means to render the driving means inoperative, and means adapted to be thrown into the path of the traverse means to actuate the stopping means.

25. In a winding machine, the combination of a winding spindle, a thread guide, traverse means including an oscillating traverse arm connected to reciprocate the thread guide, driving means for rotating the winding spindle and oscillating the traverse arm, stopping means for rendering the driving means inoperative, detent means for normally maintaining the stopping means in-

operative, and means adapted to be thrown into the path of the traverse means to release the detent means to render the stopping means inoperative.

26. In a winding machine, the combination of a winding spindle, a thread guide, traverse means including an oscillating traverse arm for reciprocating the guide, driving means for rotating the spindle and oscillating the traverse arm, stopping means for rendering the driving means inoperative, a slideable detent rod for restraining the stopping means from action, and means movable into the path of the traverse means to cause the latter to shift the detent rod to release the stopping means.

In testimony whereof I affix my signature.

JAMES DANIEL JOYCE.
